US00D972913S

(12) **United States Design Patent** (10) **Patent No.:** **US D972,913 S**
(45) **Date of Patent:** **** Dec. 20, 2022**

(54) **CAR SAFETY BELT LOCK**

(71) Applicant: **WENZHOU RUICHENG TRADING CO LTD**, Wenzhou (CN)

(72) Inventor: **Yifan Xue**, Wenzhou (CN)

(73) Assignee: **WENZHOU RUICHENG TRADING CO LTD**, Wenzhou (CN)

(**) Term: **15 Years**

(21) Appl. No.: **29/802,088**

(22) Filed: **Aug. 3, 2021**

(51) LOC (13) Cl. **08-07**

(52) U.S. Cl.

USPC **D8/333**

(58) **Field of Classification Search**
